UNITED STATES PATENT OFFICE

CLARENCE A. MICHEL, OF CLEVELAND, OHIO, ASSIGNOR TO DELCO REMY CORPORATION, OF DAYTON, OHIO, A CORPORATION OF DELAWARE

AUTOMOBILE HEADLIGHT

Application filed February 7, 1925. Serial No. 7,447.

This invention relates generally to automobile headlights and more particularly to a novel form of reflector for use in connection with a dual filament lamp and a modified 5 form of lens.

In many of the automobile headlights as now constructed, two lamps are employed, the central or driving lamp being usually of greater candle power than the upper lamp 10 which is usually termed the dimmer and is employed for city driving and when passing other automobiles, whereas the main or central light is intended for road driving. Furthermore, in most automobile headlights 15 as at present constructed some form of modified lens is employed and very frequently modified forms of reflectors in order to keep the top of the beam below a definite level which is termed the legal limit of the top of 20 the beam.

The object of my invention is to employ at the center of the reflector a lamp having two filaments one of which can be used for road driving and the other one for city driving or 25 while passing automobiles and these two filaments are so placed that, in connection with the reflector and lens, the top of the beam will always be maintained at the proper legal height but can be drawn down perceptibly for 30 city driving or when passing other automobiles.

My invention consists in the details of construction and combination hereinafter fully described and set forth in the appended 35 claim.

Various forms of reflectors and lenses might be employed for carrying out my invention and in the drawing forming a part of this specification I have shown one embodiment of such general inventive idea and in 40 which Fig. 1 is a vertical sectional view of the reflector and lamp arranged therein together with a lens arranged in advance of the reflector; Fig. 2 is a face view of the reflector; 45 Fig. 3 is a face view of the lens; and Fig. 4 is a side view thereof.

In order to carry out my invention I employ a lamp A having two independently lighted filaments B and C, the filament B 50 being arranged substantially on the axis D

of the reflector E while the filament C is arranged a short distance above the same. The lower half of the reflector E is a true parabola but the forward portion of the upper half is modified by bringing the portion be- 55

tween the points F and G within or below the true parabolic curvature of revolution, the true curvature of revolution being indicated by the dotted lines F G' whereas the ac- 60

tual curvature is within and indicated by the full line F G. If this upper forward portion of the upper half of the reflector were not thus modified the rays of light emanating from the upper filament would be 65

reflected upwardly but by bringing the cur- 70

vature within or below the true parabolic curvature, as indicated, the rays of light from both filaments will be reflected downwardly. The rays of light from both filaments re- 75

flected from the lower portion will be hori- 80

zontally directed and slightly below the hori- 85

zontal. In order to prevent the formation 90

of sharp angles between the lower half of the reflector and the modified portion and also to facilitate the fabrication of the one 95

piece reflector I provide transition surfaces 100

H between the upper and lower sections of the reflector, the side edges of such transition surfaces being indicated by the lines I. By means of the reflector as thus constructed and the two filament lamp positioned in the manner herein set forth all of the rays of light from either filament will be directed either horizontally or below the horizontal. In connection with the lamp and reflector as herein described I employ a lens K having vertical flutes L covering the major portion of the lens and flutes M covering the extreme lower portion of the lens, these flutes M being prismatic. By means of the flutes there will be lateral distribution of the light and inasmuch as the lower flutes M are prismatic there will be a bending down of the rays passing therethrough so as to prevent any possible upward tendency of the rays reflected from the forward portion of the lower half due to the fact that the filaments have considerable longitudinal dimension and consequently are in excess of the true focal point.

In use the filament B is employed for road 100

driving and the top of the beam will be projected forwardly a considerable distance in this manner the desired road illumination may be obtained. For city driving, however, 5 and when passing other automobiles the filament B will be cut out and the filament C cut in and the top of the beam will then be perceptibly deflected or thrown downwardly thereby avoiding all possibility of glare as it 10 is well understood that, owing to unevenness of the roadway or to the movement of the vehicle, there are times when stray beams are dangerous notwithstanding the fact that modified lenses and reflectors may be employed but experience has demonstrated that 15 by means of the double filament lamp in combination with the reflector and lens as herein shown and described a decided vertical deflection of the top of the beam is obtained 20 and the liability of glare reduced to a minimum.

Having thus described my invention, what I claim is:—

In a light projector, the combination of a 25 substantially parabolic reflector and a lamp, said lamp having two independently lighted filaments, one of said filaments being located on the axis of the reflector and the other one slightly above said axis, 30 the forward portion of the upper half of the reflector being brought within the true curvature of revolution whereby rays of light from either filament will be reflected downwardly, and a lens having a prismatic lower 35 portion arranged in advance of the reflector and whereby any upwardly directed ray reflected from the forward portion of the lower half of the reflector will be refracted downwardly.

10 In testimony whereof, I hereunto affix my signature.

CLARENCE A. MICHEL.
